WIRE CONNECTER

Martin D. Bergan, Linden, N. J., assignor to The Thomas & Betts Co., Elizabeth, N. J., a corporation of New Jersey

Original application April 25, 1935, Serial No. 18,112. Divided and this application April 16, 1937, Serial No. 137,161

3 Claims. (CL 173—269)

The invention relates to a solderless wire connector in which a wire or wires are secured. The wire connector is adapted to be anchored to some other structure in order to electrically connect the wire or wires with such structure. The invention relates particularly to a form of solderless wire connector which is produced by bending sheet metal blanks or ribbons to form both parts thereof and particularly to form the principal part of the connector or the clamping member.

This application is a division of my application Serial No. 18,112 filed April 25, 1935.

It is an object of the invention to construct a new and novel wire connector formed from sheet material in which the principal part of the wire connector is integral with the securing means by which the connector is secured to some other structure.

Another object is to devise a wire connector in which the parts are formed from blanks of sheet metal or metallic ribbon which are bent into new and novel form.

Other objects of the invention will be more apparent from the following description taken in connection with the accompanying drawing showing a preferred form of the invention, in which:

Figure 1 is a view in longitudinal section of the assembled wire connector gripping a wire therein.

Figure 2 is a cross-sectional view taken on line 2—2 of Figure 1.

Figure 3 is a view in side elevation showing the clamping member as it is bent or shaped to form a tapered or inclined wire receiving seat or groove.

Figure 4 is a top view of the clamping member and shows the wire receiving seat or groove formed in one end thereof.

Figure 5 is an end view of the slidable operating member by means of which a wire is clamped or gripped in the wire receiving groove or the clamping member.

Figure 6 is a longitudinal section of the operating member taken on line 6—6 of Figure 5.

Solderless wire connectors are known in which the part which immediately contacts with or grips the wire is a separate part from the means which secures the wire connector to some other structure and the two parts are secured together in some suitable way. With two parts so connected together, the electrical flow from the wire to the supporting structure is through parts physically separate from each other, even though they are in contact with each other at some point, and

hence the electrical flow or connection must be across contacting surfaces. It is preferable in wire connectors that a continuous and unbroken metallic path be provided through the wire connector. In the construction of wire connector disclosed herein, such a continuous metallic path is provided between the clamping means for the wire and the securing means by which the connector is secured to some supporting structure. The structure herein obtains the continuous metallic path for the electrical energy in a part or parts bent from sheet metal.

The wire connector to be described herein comprises two members, namely a clamping member 10 and an operating member 11. Each member is formed by bending a sheet metal blank or ribbon into a form now to be described. The clamping member has a wire seat or groove 12 which is integral with the securing means 13. One or more holes 14 are provided in the securing means to receive anchoring screws or bolts (not shown) which secure the wire connector to some other structure. Two such bolt holes are shown. The sheet metal blank or ribbon is preferably bent so that the two edges 15 thereof are raised above the normal level of the securing means, or are in a plane spaced from the plane of the securing means. The member is also bent so that an inclined wire seat or groove 12 is formed between these raised edges, which groove extends at an angle with respect to the edges. It is important that the wire groove 12 be at an angle or inclined with respect to the adjacent edges whether or not the edges are raised as illustrated. These raised edges are preferably parallel with the plane of the securing means, although such parallel relation is not necessary. The edges form guides upon the sides of the clamping member. The width of the member is narrower across the guides than the width of the ribbon or securing means, the purpose of which will appear more fully hereinafter. Serrations or biting teeth may be provided in the groove to more firmly grip the wire and to more effectively establish electrical contact therewith.

The sliding operating member 11 is shown particularly in Figures 5 and 6 and serves to anchor or clamp a wire in the inclined wire groove or seat 12. This operating means is also bent from sheet metal having its ends bent around to form the inwardly directed channels 20 for slidably receiving the edges 15 of the clamping member. The operating member preferably has an inclined wire groove 21, the incline of which extends in the same direction as the groove or wire 55

seat 12 in the clamping member 10 so that the seats formed by the groove are substantially parallel with each other. This operating member is slid upon the clamping member along the edges 5 or guides 15 which are received within the channels 20. After the operating member has been positioned upon the guides, the end of the clamping member or a pair of projections 22 thereupon are bent at right angles to the edges 15 in order to provide stops for the operating member. These stops 22 prevent the operating member from being separated or removed from the clamping member 10. The edges 15 are preferably provided narrower than the width of the securing 10 means because the greater width of the edges of the securing means also serves as a stop for the slidable operating member at this end of the edges. It will be observed, therefore, that one of the members has channels and the other 15 member has edges which are received in the channels, and the edges and channels cooperate together to form guides.

In order to secure a wire W within the wire connector, the slider or operating member 11 is 20 shifted to the left-hand end of the guides 15 upon the clamping member 10 in which position the wire passage, formed by the opposed grooves 12 and 21 in the clamping member 10 and operating member 11 respectively, is greatest. The 25 wire W has the insulation removed therefrom and this uncovered end of the wire is slipped into the wire passage. The operating member is then forcibly pushed to the right relatively to the clamping member which reduces the size of the 30 wire passage because the grooves 12 and 21 are inclined with respect to the channels 20 and the guides or edges 15, and the wire is then clamped within the wire passage. In the broader aspect of the invention, it is immaterial which member carries the channels and which part carries the edges. Both are guides and the wire seat or groove 12 must be inclined with respect to the 35 guides upon the same member.

Various modifications will occur to those skilled in the art in the configuration, composition and disposition of the component elements going to make up the invention as a whole, as well as in the selective combination or application of the respective elements, and no limitation 40 is intended by the phraseology of the foregoing description or illustrations in the accompanying drawing.

What is claimed is:

1. A wire connector comprising a clamping member formed from a ribbon of sheet metal, the edges of the sheet metal ribbon at one end thereof being pressed upwardly to form a wire receiving 5 groove therebetween, the groove being inclined with respect to the pressed up edges of the clamping member, the pressed up edges of the clamping member being parallel, an operating member carried by the clamping member and slidable 10 upon the parallel edges thereof relatively to the inclined groove to grip a wire therein, and the other end of the clamping member forming securing means to anchor the connector to some other structure. 15

2. A wire connector comprising a clamping member formed from a ribbon of sheet metal and having the edges thereof at one end pressed upwardly to form a wire receiving groove therebetween, the pressed up edges being formed narrower than the ribbon, the pressed up edges at the grooved end of the member being parallel to the grooved end of the member being parallel to form guides and the groove being inclined with respect to the edges, a securing means integral therewith formed by the other end of the clamping member, an operating member having inwardly directed channels within which the guides are received so that the operating member is 25 slidable upon the guides and relatively to the inclined groove to grip a wire therein, and the end 30 of the clamping member being bent at an angle to the pressed up edges to form a stop for preventing separation of the members. 35

3. A wire connector comprising a clamping member formed from a ribbon of sheet metal and having the edges at one end thereof pressed upwardly to form a wire receiving groove therebetween, the sides of the bent end being parallel to form guides and the groove being inclined with respect thereto, a securing means integral therewith formed by the other end of the sheet metal member, and the bottom of the groove merging with the securing means; and an operating member formed from sheet metal and having its ends bent over to form inwardly directed channels to 45 receive the guides, the operating means being slidable along the guides and relatively to the inclined groove to grip a wire therein. 40
